(57) **CLAIM**

The ornamental design for a toy vehicle, as shown and described.

DESCRIPTION

FIG. 1 is an elevation view of a front side of the toy vehicle in accordance with our new design;

FIG. 2 is a top plan view thereof;

FIG. 3 is an elevation view of the rear side thereof;

FIG. 4 is an elevation view of the left side thereof, the elevation view of the right side thereof being a mirror image;

FIG. 5 is a perspective view of the top, front and left sides thereof;

FIG. 6 is a perspective view of the top, front and right sides thereof; and,

FIG. 7 is a perspective view of the top, rear and right sides thereof.

The bottom side view of the toy vehicle of the new design is disclaimed in all orientations.

1 Claim, 7 Drawing Sheets

FIG. 7
